UNITED STATES PATENT OFFICE.

FRITZ SCHULZ, OF WEEZEN, GERMANY.

EVAPORATOR.

1,091,897.

Specification of Letters Patent. Patented Mar. 31, 1914.

Application filed August 15, 1912. Serial No. 715,178.

To all whom it may concern:

Be it known that I, FRITZ SCHULZ, merchant, of Weetzen, in the German Empire, having invented certain new and useful Improvements in and Relating to Evaporators, do hereby declare that the following is a full, clear, and exact description of the same.

The object of the present invention is to provide an improved means for heating 10 evaporators.

The arrangement of tubes in the interior of evaporators as heretofore proposed has the disadvantage that the tubes hinder the 15 process and disturb by incrustation the boiling process when the level of the liquid to be evaporated is low. It is also difficult to remove the incrustation.

In order to avoid the use of tubes it has been proposed to provide evaporators with 20 double bottoms, or to cast or arrange the tubes in the walls of the evaporating vessel. All these arrangements have, however, the 25 drawback that the utilization of the heat from the heating medium is inefficient owing to the thickness of the walls and bottom of the evaporator rendered necessary for safe working conditions and practical manufacture. It is well known that these large dimensions seriously impair the efficiency of 30 the medium used for heating the evaporator, since most of the heat is lost in heating the large masses of metal before penetrating the latter in order to reach the contents of the evaporator.

According to the present invention the greatest cross sectional surface of the heating channels face the interior of the evaporator, said channels being closed by a thin piece of metal of approximately 2 millimeters in thickness and welded in position 40 in such a manner that they lie flush with the bottom or sides of the evaporating vessel. In this manner the heat is transmitted to the interior of said vessel in an efficient manner irrespective of the thickness of the walls. The brine or other liquid is thus caused to 45 contact with the greatest surface of the heating channels covered by very thin covers,

with the result that evaporation is much more rapid than is the case when the heating 50 medium has to pass through thick masses of metal before reaching the liquid to be evaporated. The efficiency may be increased by lining the bottom of the heating channels with a material which is a bad conductor of 55 heat.

The invention is applicable to pans, boilers, and apparatus of all descriptions adapted to be heated by steam or gas, and in which false bottoms or cast in tubes have proved 60 uneconomical.

An embodiment of the invention is shown in the accompanying drawing, in which:

Figure 1 is a diagrammatic plan view and Fig. 2 a sectional perspective view on an 65 enlarged scale.

The metal plate, wall or base *a* is provided with a system of channels *b* doubling back upon themselves and open at the top. These channels are covered by thin plates *c* which 70 are welded into grooves formed in the plate *a* at the upper edges of the channels *b*, so that the top of plate *a* and the thin plates *c* lie flush with one another. In Fig. 1 the channels *b* are diagrammatically indicated 75 by lines. The total surface of said channels *b* should correspond to the particular heating surface required.

The arrangement described may be applied to the sides of the evaporator as well 80 as to the bottom of the same. The cross section of the channels *b* may be other than semicircular as shown in the drawing.

What I claim is:

An evaporator comprising a base plate 85 provided with a system of communicating heating channels, having grooved edges and with a plurality of covering plates welded within the grooved edges to cover the channels, the outer faces of the several covering 90 plates being flush with the corresponding face of the base plate.

FRITZ SCHULZ.
